CLAIM

The ornamental design for the power head for a convection oven, as shown and described.

DESCRIPTION

FIG. 1 is a top isometric view of a convection oven power head, showing our new design, in environmental use condition;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top isometric view of a convection oven power head, showing our new design;

FIG. 9 is a bottom isometric view thereof;

FIG. 10 is a front view thereof;

FIG. 11 is a rear view thereof;

FIG. 12 is a left side view thereof;

FIG. 13 is a right side view thereof;

FIG. 14 is a top view thereof; and,

FIG. 15 is a bottom view thereof.

The broken lines showing portions of the convection oven power head are for the purpose of illustrating environmental structure and form no part of the claimed design.
